UNITED STATES PATENT OFFICE

CLARENCE E. FOX, OF BEREAL, OHIO, ASSIGNOR TO THE FOX TOY COMPANY, OF BEREAL, OHIO, A CORPORATION OF OHIO

DESIGN FOR A WATER FLOAT

Application filed May 15, 1930. Serial No. 35,658. Term of patent 7 years.

To all whom it may concern:

Be it known that I, CLARENCE E. Fox, a citizen of the United States, residing at Berea, in the county of Cuyahoga and State of Ohio, have invented a new, original, and ornamental Design for Water Float, of which the following is a specification, reference being had to the accompanying drawing, forming part thereof, wherein

Fig. 1 is a top plan view and Fig. 2 a side elevation of the article, showing my new design.

I claim:
The ornamental design for a water float as shown.

CLARENCE E. FOX.
